ELECTRICAL RELAY

Filed Oct. 14, 1930

UNITED STATES PATENT OFFICE

NOBLE C. SHAW, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL RELAY

Application filed October 14, 1930. Serial No. 488,609.

My invention relates to electrical relays, and has for an object the provision of novel and improved means for assembling the relay case.

5 I will describe one form of relay embodying my invention, and will then point out the novel features thereof in a claim.

In the accompanying drawings, Fig. 1 is a front view, partly sectional, showing one 10 form of relay case assembly embodying my invention. Fig. 2 is a side view of the case shown in Fig. 1. Figs. 3 and 4 are fragmental views of parts of the relay case assembly. Fig. 5 is a bottom view of a part of 15 the relay case assembly shown in Fig. 1. Fig. 6 is an isometric view showing the method of fitting two parts of the relay case assembly. Fig. 7 is a view of a segment of the relay case assembly before it is assembled.

20 Similar reference characters refer to similar parts in all views.

Referring first to Figs. 1 and 2, the reference character 1 denotes the top plate of an electrical relay made of suitable insulating 25 material, such as porcelain or bakelite, and which carries a first row of terminal posts 19, a second row of terminal posts 20, a third row of terminal posts 21, a fourth row of terminal posts 22, a mounting spring 33 and 30 an electromagnet 18. The core of electromagnet 18 extends through top plate 1 and terminates on the underside of the top plate in pole piece 3. Armature 2 is controlled by 35 pole piece 3, and attached to armature 2 is a support 17 which carries contact springs 4^a and 5^a. Associated with contact springs 4^a and 5^a are contacts 4 and 5, respectively. The contacts and movable parts on the underside of top plate 1 are enclosed by a glass 40 case 6 which is fitted against a rectangular cork gasket 7, and is held from sliding by lugs 8, 8^a, 9 and 9^a, extending from the underside of the top plate. Integral with glass case 6 are four similar feet 34 which serve 45 as supports for the relay when mounting spring 33 is not used. The bottom of glass case 6 has a rib 35 which serves as a rest for spring 10 when the relay case is assembled. Glass case 6 is secured to top plate 50 1 by means of straps 11 and 12 and spring 10.

Strap 11 is made of a strip of metal having at the top grooves 23^a and 23^b and having at the bottom a transverse opening 24 and notches 25^a and 25^b, and the strap is so bent that it approximately conforms to the shape 55 of the side of glass case 6. The top end of strap 11 fits in a niche 16^a in top plate 1 in such manner that it can not be disengaged from the niche without swinging out away from the glass case so that the end of the 60 groove in the strap will clear the side of the top plate at point C as shown in Fig. 3. Strap 12 is similar in construction to strap 11 and fits similarly in niche 16^b as strap 11 fits in niche 16^a. Straps 11 and 12 extend downwardly along the side of the glass case and are assembled to spring 10. Spring 10 as best seen in Fig. 5 is made of a strip of metal having at one end a U-shaped opening forming 65 the part 27 and having at the other end a longitudinal opening 14, a transverse opening 28 and a hole 36. Assembled in opening 14 is a key 13 and as best seen in Fig. 7, key 13 comprises a rectangular strip of metal 32 having a hole 29, grooves 30^a and 30^b, and notches 31^a and 31^b. Key 13 is assembled to 70 spring 10 so that it may be moved from one end to the other of opening 14 and is held in line with the opening but cannot be removed. The key, as shown in Fig. 7, is first inserted 75 through slot 14 and bent in such a manner that the wide portions of the key are on opposite sides of the spring with the narrow sections sliding in the slot as a guide. This assembly of spring 10 and key 13 is of advantage 80 in providing a means for holding the key in position for use at all times and avoids the possibility of its being lost while assembling or dismantling the relay case.

In assembling, the relay case 6 is first 85 placed against the gasket 7 and straps 11 and 12 are placed in niches 16^a and 16^b, respectively. The end of strap 11 is inserted through opening 26 of spring 10 so that part 90 27 engages opening 24 of strap 11. This assembly of the lower end of strap 11 and one end of spring 10 is shown in Fig. 6. The other end of spring 10 is then bent upward so that the end of strap 12 passes through opening 28. At the time of this operation, key 13 95 100

is moved in opening 14 so that the end of the key is passed through the transverse opening in strap 12 until hole 29 in key 13 is in alignment with hole 36 in spring 10. The spring 5 10 is now under compression against the glass case and holds the straps 11 and 12 in place. A wire 37 of lead seal 15 is placed through holes 36 and 29 and when the wire is fastened in the lead seal, it is impossible to 10 open the relay without breaking the seal.

One advantage of this type of relay case assembly is the elimination of any case assembly parts from the inside of the glass case, thus preventing the possibility of causing 15 loose particles of dirt or chips in the relay while assembling the case. Another advantage is the elimination of excessive strains on the top plate and case which may affect relay calibration or cause the glass case to break.

20 Although I have herein shown and described only one form of relay case embodying my invention, it is understood that various changes and modifications may be made therein within the scope of the appended 25 claim without departing from the spirit and scope of my invention.

Having thus described my invention, what I claim is:

An electrical relay having an insulating 30 top plate provided with two peripheral niches and with a plurality of metallic lugs projecting from the undersurface, a glass case coacting with the undersurface of said top plate and prevented from sliding by said 35 lugs, a spring having a U-shaped opening in one end and having in the other end a transverse opening and a longitudinal opening and a hole, a key in said longitudinal opening assembled to slide in said opening but 40 not to be disengaged therefrom, a first and a second side strap each having two grooves at one end for hooking such end in each of said niches and each having at the other end a transverse opening and two notches, the end 45 of said first strap projecting through said U-shaped opening in said spring and secured thereto, the end of said second strap projecting through said transverse opening in said spring, and the end of said key in said 50 longitudinal opening in said spring being passed through said transverse opening in said second strap.

In testimony whereof I affix my signature.

NOBLE C. SHAW.
